F. O. ALLMAN

COMBINATION WINDOW SASH

Filed Feb. 1, 1922

INVENTOR:

Frank O. Allman
BY, A. M. Carlsen
ATTORNEY:

Patented June 2, 1925.

UNITED STATES PATENT OFFICE.

FRANK O. ALLMAN, OF ST. PAUL, MINNESOTA.

COMBINATION WINDOW SASH.

Application filed February 1, 1922. Serial No. 533,318.

To all whom it may concern:

Be it known that I, FRANK O. ALLMAN, a citizen of the United States, residing at St. Paul, in the county of Ramsey and State 5 of Minnesota, have invented a new and useful Combination Window Sash, of which the following is a specification.

My invention relates to combined storm sash and screen sash for windows. The 10 object of the invention is to enable storm sash and screens to be easily exchanged at the end of cold and warm seasons and also to make said parts easy to repair when either the window glass or the wire netting of same 15 may need repairs or replacing.

In the accompanying drawing,

Fig. 1 is an elevation of the inner side of my device ready to be put into the regular recess for storm sash in a building (not 20 shown). The upper sash is shown as holding a screen and the lower sash as holding a pane of glass, to avoid unnecessary drawing, but in actual use both upper and lower sash hold glass in the winter season and screens 25 in the summer season and may be made of any suitable material.

Fig. 2 is an enlarged section on line 2—2 in Fig. 1.

Fig. 3 is an enlarged section on line 3—3 30 in Fig. 1 with the top and bottom bars of the sash indicated as if made of wood.

Fig. 4 is an enlarged section on line 4—4 in Fig. 1 and indicating that most of the parts may be made of metal.

Fig. 5 is an enlargement of the lower portion of one of the screen holding sashes in my device regardless of material used; and the view shows means for stretching the inserted screen.

Fig. 6 is an enlarged portion of the upper sash and the handle on same.

Fig. 7 is a section on line 7—7 in Fig. 6 with the sash shown hollow as when made of sheet metal, although it may also be of wood.

Referring to the drawing by reference numerals, 10 designates a wooden sash as large as the entire window opening in the building. As this sash is to be secured permanently in place in the recess in the window frame (not shown) usually provided for storm sash, I will call it the fixed sash.

Normally fitted to slide vertically in the fixed sash are two removable sashes 11 having wire netting 13, or two sashes 12 having glass 14. In the drawing one of each of said

sashes is shown as sufficient for explanation and the other two being duplicates of those shown are omitted.

Each sash 11 and 12 is preferably made 60 of sheet metal and formed with overlapping hook-shaped flanges 15—16 (see Fig. 2) forming a tight joint when both sashes are closed. Each slideable sash is also formed with opposite grooves 17 adapted to 65 slidably receive vertical metal ribs 18—19 in the fixed sash 10. Each sliding upper sash also has an end groove 20 fitting over a horizontal top rib 21, and each lower sash has a similar groove 22 (see Fig. 2) for a bottom rib 23. In all of said grooves may be disposed inlaid strips like 24^a of soft material to make air tight joints.

Each movable sash has a handle 25 to take hold of in moving the sash and a slideable 75 catch 26 adapted to engage in notches 27 in the guiding ribs 18 and 19; each catch having a finger operated button 28.

In the upper sash there is a channel 29 for the button 28 to slide in so as to not obstruct the rising movement of the lower sash; for the same purpose the upper handle 25 is also placed in a cavity 25^a in the sash and is pivotally held at its ends 25^b so it may be swung out of the cavity while in 85 actual use.

One of each sash guiding ribs, say 19, extends all the way up and down in the fixed sash, while the other or opposite rib 18 extends only about half way up for the sash 12 90 and half way down for the sash 11, so that by moving the lower sash fully upward one edge of it may be pushed out of the fixed sash and the other edge then pulled away from its long guiding rib, and the top sash 95 may likewise be removed from its extreme bottom position. It is in this manner that two screen sashes may readily be removed and two glazed sashes substituted therefor, and in the spring the storm sashes are 100 replaced by screen sashes.

To describe the slideable sashes more in detail, it will be seen in Fig. 4 that in my preferred form each sash 11 and 12 is made 105 of sheet metal in such a way that its rails or bars are hollow inside and formed with outward guiding grooves 17 for the guiding ribs and inward grooves 17^a for either glass or wire screen. When the sash is glazed I 110 employ soft packing strips like 24^a in Figs. 1 and 7 to make a draft-tight joint about the edges of the glass. Each sash has its top

rail formed with a slot 35*, down through which the glass, or the screen is pushed until it stops in a groove 35 in the bottom rail. This will in the outer or top sash 11 in Figs. 5 and 3 leave a groove 20 to receive the fixed rib 21 of the lintel 10, and in the lower sash 12 the top slot 35* is closed or filled by a strip 30 which is removably secured by a screw 31 (shown in Fig 2). This makes either glass or screen readily removable for repair or exchange.

In the sash holding the screen 13, the screen has each of its vertical edges firmly clamped in a sheet metal channel strip 32 (see Fig. 4) while the top and bottom edge may be simply the raw edges of the net as woven. After the channel strips 32 are pushed into the inward grooves of the sash the netting is stretched in horizontal direction by forcing a light flat bar 33 between the lower ends of the channel strips 32, and a similar bar 34 between the upper ends of said strips. Such bar 33 or 34 is first placed

at an incline, as shown in Fig. 5, and is then forced into horizontal position at one side 2 of the screen wire, one bar into the lower groove 35 (see Fig. 3) and the other upwardly partly into the slot 35** down through which the screen is inserted before being stretched.

What I claim is:

A window sash having in its top rail a slit and in its vertical stiles inward grooves extending downwardly from the ends of said slit; a wire netting inserted in said sash and 35 a strip removably held in said slit to close it; said wire netting having its vertical edges clamped tightly in channel bars, and loose horizontal bars inserted one across the top and the other across the bottom end of the 40 netting and engaging the ends of the channel bars to hold them with the wire netting stretched, said cross bars being received into the sash at one side of the netting.

In testimony whereof I affix my signature.
FRANK O. ALLMAN.
